CLAIM

The ornamental design for a filter cartridge having a manifold engagement portion, as shown and described.

DESCRIPTION

FIG. 1 is top, front, and right-side perspective view of a filter cartridge having a manifold engagement portion;

FIG. 2 is another top, front, and right side perspective view of the filter cartridge having a manifold engagement portion; FIG. 3 is a top view of the filter cartridge having a manifold engagement portion;

FIG. 4 is a bottom view of the filter cartridge having a manifold engagement portion;

FIG. 5 is a front view of the filter cartridge having a manifold engagement portion; and,

FIG. 6 is a right-side view of the filter cartridge having a manifold engagement portion.

The left-side and rear views are substantially the same as the right-side and front views, respectively.
